UNITED STATES PATENT OFFICE.

FRED J. BOSSERT AND CHARLES T. BOSSERT, OF SELMA, CALIFORNIA.

VINE-CUTTER.

1,338,281.

Specification of Letters Patent. Patented Apr. 27, 1920.

Application filed October 3, 1919. Serial No. 328,167.

To all whom it may concern:

Be it known that we, FRED J. BOSSERT and CHARLES T. BOSSERT, citizens of the United States, residing at Selma, in the county of Fresno and State of California, have invented certain new and useful Improvements in Vine-Cutters, of which the following is a specification.

This invention relates to improvements in vine cutters and more particularly to devices adapted for use in cutting bunches of grapes and the like from the vine.

An important object of the invention is to provide a device of the above mentioned character which is simple in construction, inexpensive to manufacture and expeditious and convenient in use.

A further object is to improve the device shown in our Patent Number 1,265,296.

Other objects and advantages of the invention will be apparent during the course of the following description.

In the accompanying drawings forming a part of this specification and in which like numerals are employed to designate like parts—

Figure 1 is a perspective view showing our device in use.

Fig. 2 is a perspective of our device, detached, the view being taken from the rear side thereof.

Fig. 3 is a perspective taken from the opposite side of the device.

Fig. 4 is a longitudinal sectional view thereof, and

Fig. 5 is a section taken on the line 5—5 of Fig. 4.

Referring now more particularly to the drawings, the numeral 10 indicates a body portion or shank bent rearwardly at its upper end as at 11.

Beyond the bend 11 from the shank the body portion is bent as at 12 to form a blade 13 extending over the shank 10 and angularly disposed thereto. It will be noted that the bend at 12 is such that the blade is transversely and longitudinally at an angle to the shank 10. The blade 13 is provided on its longitudinal sides with cutting edges 14 and 15, and the upper end of the blade is provided with a V-shaped notch 16. The notch 16 has its edges preferably blunt to constitute non-cutting edges, which may be advantageously employed in removing or

separating the vine to be cut from the associated vines. 55

To prevent the metal of the cutter from coming into contact with the hand of the user a leather guard is provided comprising a body portion 17 having flaps 18 and 19 adapted to be folded about the body of the shank. A rivet 20 extends through the body portion of the shank 10 and the flaps 18 and 19 securing them together. The lower end of the body portion 17 is provided with an end flap 21 extending about the lower end 60 of the shank 10 and held in position by a rivet 22, extending through the body portion 17, shank 10 and the flap 21. The rivet 22 also extends through the material 70 of a buckle loop 23 carrying a buckle 24.

The upper end of the body portion 17 is secured to the shank 10 adjacent the bends 11 and 12 thereof by means of rivets 25, 26 and 27, these rivets being so arranged as to hold the upper end of the body portion 75 in close engagement with the shank. The body portion 17 of the guard is provided with transverse slits 28 and 29 forming straps 30. The upper end of the guard is reduced and 80 extends through the straps 30 and is provided adjacent its end with openings 32 to receive the buckle pin 33.

It will be seen that where in our previous patent the strap by means of which the cutter is secured to the hand extends about the whole hand and is adapted to engage the hand adjacent the knuckles, in the present device the strap engages but the first and 4th fingers of the hand and these between the 85 second and third joints thereof. We have found that the metal guard or holder of our previous patent had a tendency to chafe the hand and that as the guard had no means to prevent slipping of the device this chafing 90 was accentuated. In the present device however when the hand is bent as it will be in grasping a bunch of grapes, the position of the guard is such as to absolutely prevent slipping thereof. Furthermore we have 100 found that a blade having the same transverse angle as the shank thereof does not assume the proper cutting relation with the stem to be cut. This fallacy has been overcome by disposing the blade at an angle to 105 the shank both transversely and longitudinally.

It is to be understood that the form of

our invention herewith shown and described is to be taken as a preferred example of the same and that various changes in the shape, size, and arrangement of parts may be 5 sorted to without departing from the spirit of the invention or the scope of the subjoined claims.

What we claim is:

1. A vine cutter comprising a plate, a 10 blade offset therefrom and angularly disposed thereto longitudinally and transversely, a covering of leather arranged on one side of said plate, extensions formed on each side of said leather covering, said extensions being arranged over the opposite side of said plate and secured thereto, a 15 strap formed on one end of said covering, said strap being adapted to overlie the body portion of the covering, means for forming 20 loops between the body portion and the strap, and means for securing the free end of said strap.
2. A vine cutter comprising a plate, a blade offset therefrom and angularly disposed thereto longitudinally and transversely, a covering of leather arranged on one side of said plate, extensions formed on each side of said leather covering, said extensions being arranged over the opposite 25 side of said plate and secured thereto, a strap formed on one end of said covering, said strap being adapted to overlie the body portion of the covering, the body portion being provided with transverse slits, said 30

strap being adapted to be received in said 35 slits to form loops, and means for securing the free end of the strap.

3. In a vine cutter a shank and a blade offset from the shank, said blade being angularly disposed to said shank longitudinally and transversely, and means for preventing the metal of said shank from contacting the hand comprising, a body portion formed of leather or the like and provided with flaps folding about said shank, a rivet 40 extending through said body portion, shank and flaps, an end flap formed upon said body portion and extending about the lower end of said shank, a rivet extending through said body portion, shank and end flap, a buckle loop also secured to said shank by said last named rivet and carrying a buckle, rivets securing the upper end of said body portion to said shank at the offset 45 thereof connecting the shank, and blade 50 straps formed upon said body portion, the upper end of said body portion extending downwardly through said loops, the extremity of said upper end being provided with openings adapted to co-act with the 55 pin of said buckle.

In testimony whereof we affix our signatures in presence of two witnesses.

FRED J. BOSSERT.

CHARLES T. BOSSERT.
